CLAIM

The ornamental design for a container insulator, as shown and described.

DESCRIPTION

FIG. 1 is an overhead perspective view of a container insulator showing our new design;

FIG. 2 is a front view of the container insulator shown in FIG. 1;

FIG. 3 is an overhead view of the container insulator shown in FIG. 1;

FIG. 4 is an underneath view of the container insulator shown in FIG. 1;

FIG. 5 is a rear view of the container insulator shown in FIG. 1;

FIG. 6 is a first side view of the container insulator shown in FIG. 1;

FIG. 7 is a second side view of the container insulator shown in FIG. 1; and,

FIG. 8 is a cross-sectional view showing a section taken along line 8-8 of FIG. 5.

(Continued)

The broken lines shown in the drawings are for the purpose of illustrating portions of the container insulator that form no part of the claimed design.

1 Claim, 5 Drawing Sheets
